HINGE

Charles Colucci, New York, N. Y.

Application May 16, 1938, Serial No. 208,138

7 Claims. (Cl. 16—153)

This invention relates to hinges, and particularly to improvements in pin hinges having cam characteristics wherein the moving leaf has a rise or fall while rotating, and may obtain a sustained rise or fall through 180 degrees of swing.

While hinges embodying cam features have been heretofore proposed, it has been principally for gravity acting hinges capable of short swings and utilizing the cam action as a means of 10 turning the active leaves and the door or the like they generally supported, to closed position. Some of these hinges by utilizing loose expensive cam parts were capable of permitting short swings right or left. However, for wide swings it was 15 necessary to use a different hinge for a right swing than for a left swing. Moreover, only in exceptional cases and then only with a single acting hinge having loose cam parts that had to be re-positioned and maintained in position by auxiliary 20 parts requiring close fitting and which were readily lost was it possible to use a cam hinge as an ordinary hinge. These hinges have never insofar as I am aware found favor, possibly because they were not adapted to universal operation, i. e., operate 25 right, left, or neutral and be capable under each condition, of sustained swings of 180 degrees and have the mounting simplicity of the ordinary hinges still used.

It is also to be observed that in the conventional door and frame combination, the door is hung by plain pin hinges so that its lower end has considerable clearance when swinging, relative to the face of the floor. In order to close the frame opening when the door is in closed position a saddle board is secured to the floor just under the door. Such saddle boards are a source of tripping and other inconvenience in the home. They are also an unsightly encumbrance between rooms connected by French doors. Moreover, 30 some clearance is also necessary between the lower end of the door and the face of the saddle board and when this is considerable, air drafts may result. Insofar as I am aware, no pin hinge has heretofore been provided making possible the 35 elimination of saddle boards and their undesirable features, yet that is capable of providing the door with operating clearances equivalent to those heretofore obtained by the use of a saddle board and which hinge could also be used as a plain 40 hinge in a saddle board construction when required.

It is the purpose of the present invention to provide a cam type hinge of simple construction which may, by a simple adjustment and with the 45 same pair of leaves be operated as a left, right,

or neutral hinge, which I term for convenience a universal hinge. It also aims to overcome the aforesaid difficulties of prior art hinges and to be applicable to any character of operation now performed by a cam or an ordinary hinge. It also makes possible the elimination of door saddle boards and the like. It requires stocking of only a single type hinge by the dealer. Its parts are all intact and no mechanic is needed for their application or adjustment from one use to another. Moreover the character of operation may be altered without removing the hinge leaves.

Further objects of the invention are the provision of a cam type pin hinge of universal operation wherein all the cam faces are part of the 15 knuckles fixed to the leaves; the provision of a universal type cam hinge that may be adjusted for the desired operation without the handling of many loose parts; the provision of a cam type hinge which may by the inclusion of a loose collar be operated in one direction as a self raising 20 or lowering hinge and in the other as a neutral hinge; the provision of a gravity cam hinge operable left or right and convertible to a neutral hinge by the use of a loose collar interposed between certain hinge knuckles; and the provision 25 of a cam hinge capable of producing a continuous rise or fall through an operation of 180 degrees.

Moreover it is an object of my invention to provide a simple cover for hinges particularly cam 30 hinges comprising a U shaped member of sheet material held in place by resilient end straps secured to the hinge pintle and permitting motion of the cover piece in response to movement of the hinge leaves.

These and other objects of the invention relating to the improved hinge and cover member, the novel association of parts and the improved assembly and application thereof, and all its parts and combinations, will in part be obvious and in part be pointed out in the subsequent detailed description and in the accompanying drawing forming a part thereof and in the claims. The drawing merely illustrates a preferred embodiment and is not to be considered as limiting the 45 invention to the embodiment shown and described. All modifications including features of construction, combinations of elements and arrangement of parts as may be within the spirit of the invention are therefore contemplated.

In the drawing wherein similar parts are designated by similar numerals

Fig. 1 is a plan view of the hinge of my invention in open position and adjusted to operate as a neutral hinge

Fig. 2 is a cross-sectional view taken at 2—2 of Fig. 1

Fig. 3 is a side elevation of the hinge of Fig. 1 in closed position and adjusted to operate as a "left" cam hinge, the superposed leaf being shown in its lowermost position.

Fig. 4 is an edge elevation of the closed hinge of Fig. 3 looking in the direction of arrows 4—4 of Fig. 3

10 Fig. 5 is a side elevation of the hinge of Fig. 1 in closed position and adjusted to operate as a "right" cam hinge, the superposed leaf being shown in its lowermost position.

15 Fig. 6 is an edge elevation of the closed hinge of Fig. 5 looking in the direction of arrows 6—6 of Fig. 5 and showing a cover member partly in cross-section

20 Fig. 7 is an end view of the pintle of the hinge of Fig. 6 showing the manner of holding the cover member in place, and

Fig. 8 is a modification of the pintle construction of Fig. 2.

Referring to the drawing, 10 and 12 are cooperating leaves of a hinge constructed in accordance with the principles of my invention, and connected through the axis of a plurality of knuckles by a bolt or pintle 14. Generally a plurality of such hinges are used to support a swinging door or the like. One leaf of each hinge being on the door and the other on the stationary frame.

Manifestly to obtain a cam effect it is essential, either leaf being considered stationary, that the moving leaf obtain a rising as well as swinging motion in going from the closed position to the maximum open position. By the closed position is meant that position of the moving leaf at the bottom of its rise. Where a swing of 180 degrees is required such as with the ordinary door a sustained rise through the entire swing could be expected.

I have discovered that a right and left cam operation each capable of the desired 180 degree swing may be obtained in a single hinge in a simple and practical manner. To accomplish this result I provide two pairs of cooperating cam surfaces, one pair of which functions at any given time. Moreover one cam surface of a pair is always on one leaf and the second is on the other leaf, and that upon the stationary leaf serves as the cam while that upon the movable leaf serves as the follower.

Thus in the embodiment illustrated in the drawing I provide upon the leaf 10 a laterally projecting hinge knuckle 16, and upon the leaf 12 the laterally projecting hinge knuckles 18 and 20 which in the assembled relation straddle the knuckle 16. The knuckle 16 has opposite axial end faces sloping with respect to the hinge axis. The lower face of the knuckle 16 and the upper face of the knuckle 20 are similarly sloped. In the drawing these faces are shown as slabbed off to form substantially flat surfaces. These surfaces provide the cam surfaces referred to above, the lower surface of the knuckle 16 and the upper of knuckle 20 providing one cooperating pair and the other two surfaces the second cooperating pair.

It will be noted that the sloping faces are cut normal (Figs. 2, 4 and 6) to the edge plane of the leaves, producing a closed position when the leaves abut. However, I desire it understood that the angle between the plane of the sloping faces and the edge plane of the leaves may be varied to shift the closed position. Moreover, it will be understood that the slope of the cam surfaces

with respect to the hinge axis will be dependent upon the amount of cam rise desired. In general it need not exceed $\frac{1}{8}$ ". In many cases I have obtained satisfactory results with a cam rise of $\frac{1}{4}$ " or even less. In these operations the hinge or the member it carries must be operated through the angle of motion. For a gravity hinge that is one where the door will be self-closing or operating by action of gravity when released from its high cam point a sharp slope of greater than about 45 degrees is preferred for the cam faces, although an angle of 45 degrees somewhat as shown in the drawing will be effective.

In Figs. 3 and 4, the leaves are shown in closed position, with the cooperating sloping faces of knuckles 16 and 20 in full abutment (zero rise). Considering the leaf 12 the stationary or door casing leaf, the leaf 10 or door leaf executes a "left" swing in opening and simultaneously executes a rising movement. In the rising motion the outer portion of the sloping face of the knuckle 20 cams with the outer portion of the adjacent sloping face of knuckle 16 and these form the cam surfaces, the lower one serving as the cam and the upper as the cam follower. The length of the cam surface will obviously be dependent upon the amount of swing; generally it will not exceed 180 degrees but it will be understood that it may be greater. In the drawing a swing of 180 degrees is shown. It will also be understood that while I have illustrated the cam surface as a flat plane it may be in the form of a spiral for instance having a flat top (like a spiral staircase) or other surface depending upon the amount of contact desired. Moreover the slope may be altered, for instance at the ends to provide a rest when the hinge acts as a gravity hinge.

It will be observed that if the hinge in the position of Fig. 3 be inverted the same cam surfaces will cooperate when this time the leaf 10 is considered stationary and the leaf 12 movable and executing a left swing and rise. The cam surface of knuckle 16 now serves as the cam and that of the knuckle 20 as the follower.

In Figs. 5 and 6 the leaves are also shown in closed position and set for a right swing. Here in Fig. 5, the leaf 10 is the rear leaf and the hinge axis is to the right of the hinge leaves. In moving the leaves into this position, the cooperating sloping faces of the knuckles 16 and 18 here shown in abutment provide the cam action. Thus considering the leaf 10 again as the stationary leaf, the leaf 12 executes a "right" swing in opening together with a rising movement. In this instance it is the inner portion of the sloping face of the knuckle 18, serving as the cam follower, that cams with the inner portion of the sloping face of the knuckle 16, acting as the cam which provides the cam surfaces.

If the hinge in the position shown in Fig. 5 be inverted it will be noted that the same cam surfaces will cooperate when the leaf 12 is considered stationary and the leaf 10 movable and executing a right swing and rise.

Thus the described combination of cooperating cam surfaces when provided in the same hinge will enable its use as a cam hinge providing a swinging leaf having a simultaneous rise and capable of 180 degree swing either right or left. It is to be observed that while the cam surfaces in the drawing have a certain direction of slope, similar to that of a right hand thread, looking at Figs. 4 and 6, the respective cam sur-

faces may be oppositely sloped (left) with equal effect such merely altering (with the leaves in the drawing) the respective stationary and moving relation.

It is also to be observed that whether right or left the relation of the knuckles 16, 18 and 20 in the open position of the hinge is shown in Fig. 1, and the distance between the facing cam surfaces of knuckles 18 and 20 measured on a line parallel to the hinge axis is substantially equal to twice the cam rise of one set of cooperating cam surfaces plus the vertical thickness of the knuckle 16. If the cam rise of the two sets of cam surfaces be equal then the measured distance is substantially equal to the total cam rise of the two sets of cooperating cam surfaces (the leaf rise operating left plus the leaf rise operating right) plus the vertical thickness of the knuckle 16.

A further feature of my invention is the additional ability of my hinge to operate as an ordinary or neutral hinge of no cam action. Thus I provide two additional knuckles 22 and 24 to cooperate with the knuckles 16, 18 and 20. The knuckle 24 is at the end of leaf 12 and has its inner or operating face cut square with the hinge axis to provide a full bearing face in operation of the hinge. The outer face of this knuckle is also cut square to provide a stop shoulder for the head 26 of the pintle 14. Similarly knuckle 18 has its other axial face cut square to provide an operating bearing face and the axial distance between this face and the operating face of knuckle 24 is the sum of the right and left cam rises plus the axial height of knuckle 22. The knuckle 22 is on the leaf 10. Its opposite faces are cut square with the hinge axis and it is distant from its companion knuckle 16 a distance measured along a parallel to the hinge axis when the hinge is in closed position, equal to the sum of the right and left cam rises plus the vertical height or thickness of knuckle 18 on the line where the measurement is taken.

In addition to the knuckles 22 and 24 I provide a loose collar which together with them effects the neutral operation. In Figs. 3 and 4 a loose collar 28 is shown between knuckles 22 and 24. The thickness of this collar is equal to the "right" cam rise. It will be noted that in the indicated position this collar does not interfere with the "left" cam action of the hinge. However, if the hinge leaf 10 is made stationary instead of the leaf 12, the knuckle 24 bears against the collar 28 and the hinge operates as an ordinary or neutral hinge. This relation may be seen in Figs. 1 and 2.

In Figs. 5 and 6 a loose collar 30 is shown between knuckles 18 and 22. The thickness of this collar is equal to the "right" cam rise. The collar does not interfere with the right cam action of the hinge. However if the leaf 12 is made stationary instead of leaf 10, the knuckle 22 bears against the collar 30 and the hinge operates as an ordinary or neutral hinge. This relation may also be seen in Figs. 1 and 2.

Thus it will be evident that a "neutral" action hinge to operate either left or right may be obtained by the additional two cooperating knuckles and a loose collar. It will be understood that when the left and right cam rises are the same which will except for rare instances be the case, the collars 28 and 30 will have the same thickness and therefore a single collar will suffice, it being merely necessary to shift the collar to the proper position. This means that there are no

loose pieces to be stored elsewhere if the hinge is to be used in one form or another. Therefore all operating parts are always together and a hinge used today as a cam hinge may be used tomorrow as an ordinary hinge. Of course the extra collar may be used if desired but can only be assembled when operating the hinge neutral. At other times the extra collar may if desired be assembled under the nut 32 which is in threaded relation with the pintle 14 and may be unwound in placing the collar or disassembling the hinge. The lower face of knuckle 20 is cut square with the hinge axis to make a good facing for the nut 32. The nut 32 may if desired be pinned to prevent unwinding.

The leaves of the hinge may be made of any suitable metal for instance brass, bronze or steel. They may be cast with the knuckles intact, the cam faces and other essential finished faces being properly machined and the knuckles bored out along the hinge axis to receive the pintle 14. Preferably, the leaves together with their integral knuckles are developed out of flat sheet metal; the knuckle portions being properly developed in the flat form and then bent around a forming pin of similar diameter to the pintle 14.

The leaves are provided with suitable drilled or punched and countersunk holes 34 for mounting the hinges with flat head screws. The countersunk sides are on the inside faces of the closed hinge. It will be noted from Fig. 2 that in forming the hinge the countersunk face of each leaf is in line with the hinge axis. It will also be observed from Fig. 8 that one end of the pintle instead of being threaded and having a loose nut 32 may have a stub head 55, the shank of which is tight in knuckle 20. The remainder of the pintle is a removable pin 56 having a head similar to that of 26 of Fig. 2. Obviously the pintle may be a straight pin having no end heads.

Another feature of my invention is the provision of a cooperating cover or shield that masks the operating parts when the hinge is assembled with respect to a door and frame and which shifts slightly in response to movement of the leaves, removing away when the leaves open up and returning with them when they close.

This structure is shown in position over a closed hinge in Figs. 5 and 7. The cover comprises a U shaped, preferably sheet metal member 36 substantially coextensive with the knuckle portions of the leaves. The inner radius of the curved portion 38 is slightly larger than that of the knuckles to provide operating clearance. The sides 40 and 42 extend beyond the hinge axis a suitable amount to mask as much of the knuckle portions of the hinge as operably possible. Thus in Fig. 5 they extend almost to the edge 44 of the hinge leaves. At the opposite ends the side portions of the cover are shaped to form the ears 46. The ears 46, have holes 48, and these holes open into the end edges of the ears 46 by slits or slots 50.

In order to mount the cover piece, I provide at each end a resilient member 52 for instance a tension coil spring of small outside diameter the ends of which are connected to the holes 48 of the opposite ears 46. In assembly these resilient springs are snapped over the pintle head 26 and nut 32 which are so shaped as to provide a reduced portion into which the sides of the springs may nest. It will be readily seen that my cover member is simple in construction and may be easily positioned or removed. Moreover when the leaves open the side faces of the hinge leaves

come in contact with the edges 54 of the cover, and the cover is pushed outwardly. The resilient springs 52 respond to this movement by extending. When the hinge is again closed the springs contract and return the cover to normal position.

From a consideration of the foregoing description of the embodiments of my invention it will be evident that I have made a new and novel hinge providing in a single unit a right and left 10 cam action of considerable extent and a single hinge having these features as well as that of operating neutral thus making a universal hinge. Moreover I have provided a simple and novel cover member to cooperate with my hinge to 15 cover the operating parts and provide a neat and effective appearance when installed. My hinge and cover member are further easily assembled and installed together. It will be understood by those skilled in the art that various changes and 20 modifications may be made without departing from the spirit of my invention. I therefore desire to secure to myself all modifications and equivalent constructions falling within the spirit and scope of the invention as expressed in the 25 foregoing description, and I desire that the invention be construed to cover all equivalents and as broadly as the claims taken in conjunction with the prior art may allow.

I claim:

30 1. A hinge adapted to operate as a right or left cam hinge comprising a pair of leaves, said leaves provided with knuckles joined by a pintle, a pair of said knuckles spaced apart on one leaf, the nearest end faces of said spaced knuckles 35 having inclined cam surfaces, a third knuckle between said spaced pair having opposite end faces with inclined cam surfaces of similar slope respectively to the nearest cam surface of said spaced knuckles and adapted to cooperate therewith when camming, said third knuckle being 40 on the other leaf; the distance between said pair of spaced apart knuckles measured along a parallel to the hinge axis being substantially twice the cam rise of one set of cooperating cam surfaces plus the width of said intermediate knuckle.

45 2. A hinge adapted to operate as a right or left cam hinge comprising a pair of leaves provided with knuckles joined by a pintle, a pair of said knuckles spaced apart on one leaf, the nearest end faces thereof having inclined cam surfaces, a third knuckle on the other leaf between said spaced pair having its opposite end faces presenting inclined cam surfaces and a fourth knuckle on said other leaf, said fourth knuckle spaced from said third knuckle a distance to allow for 50 one of said pair of knuckles, for the cam action thereof and for the cam action of the other of said pair of knuckles.

55 3. A universal hinge comprising a pair of leaves provided with knuckles joined by a pintle, a pair of said knuckles spaced apart on one leaf, the nearest end faces thereof having inclined cam surfaces, a third knuckle on the second leaf between said pair of knuckles having its opposite end faces presenting inclined cam surfaces, a fourth knuckle on said first leaf spaced from one of said pair of knuckles, and a fifth knuckle

on said second leaf between said fourth knuckle and said pair of knuckles and a spacer adjacent said fifth knuckle, said fourth knuckle being distant from the nearest of said pair of knuckles to allow for the width of said fifth knuckle, the width of said spacer and the cam rise of one of said pair of knuckles.

4. A universal hinge comprising a pair of leaves provided with knuckles joined by a pintle, a pair of knuckles on one leaf, the nearest end faces thereof having inclined cam surfaces, a third knuckle on the second leaf positioned between said pair of knuckles and having its opposite end faces presenting inclined cam surfaces and a fourth knuckle on said second leaf spaced from 10 said third knuckle to allow for one of said pair of knuckles of the first leaf, the cam movement of said knuckle and for a spacer.

5. A universal hinge comprising a pair of leaves provided with knuckles joined by a pintle, a pair of said knuckles spaced apart on one leaf, the nearest end faces thereof having inclined cam surfaces, a third knuckle on the second leaf between said pair of knuckles having its opposite end faces presenting inclined cam surfaces, a fourth knuckle on said first leaf and spaced from 15 said pair of knuckles and a fifth knuckle on said second leaf between said fourth knuckle and said pair of knuckles and a spacer adjacent said fifth knuckle and between said fourth knuckle and the 20 nearest of said pair of knuckles.

6. A universal hinge comprising a pair of leaves provided with knuckles joined by a pintle, a pair of said knuckles spaced apart on one leaf, the nearest end faces thereof having inclined cam surfaces and the furthest end faces being substantially square with the hinge axis, a third knuckle on the second leaf between said pair of knuckles having its opposite end faces presenting inclined cam surfaces, a fourth knuckle on 25 said first leaf and spaced from said pair of knuckles and a fifth knuckle on said second leaf between said fourth knuckle and said pair of knuckles, said fourth and fifth knuckles having square end faces and a spacer having square end faces, adjacent said fifth knuckle and between said fourth knuckle and the nearest of said pair of knuckles.

7. A universal hinge comprising a pair of leaves, said leaves provided with knuckles joined 30 by a pintle, a pair of said knuckles spaced apart on one leaf, the nearest end faces thereof having inclined cam surfaces, a third knuckle on said second leaf, between said pair of knuckles, having its opposite end faces with inclined cam surfaces 35 adapted to cooperate with the nearest cam surfaces respectively of said spaced knuckles, when camming, a fourth knuckle on said second leaf spaced from the nearest of said pair of knuckles the cam rise of one pair of said cooperating cam surfaces when said surfaces are at the top of the cam rise, a fifth knuckle on said first leaf 40 spaced from said fourth knuckle the cam rise of the other of said cooperating cam surfaces and a spacer filling one of said spaces adjacent said fourth knuckle.

CHARLES COLUCCI.
